(57) **CLAIM**

I claim the ornamental design for a halogen table lamp, as shown and described.

DESCRIPTION

The claimed halogen table lamp is used for lighting and could stand on a table.

FIG. 1 is an elevational view of a first side of a halogen table lamp showing my new design, the elevational view of a second side and the elevational view of a third side being identical to said first side elevational view. The broken line illustration of the electrical cord shown on the claimed design forms no part thereof; and,

FIG. 2 is a perspective view thereof on a reduced scale.
